[57] CLAIM

The ornamental design for a pocketed security I.D. undergarment, as shown and described.

DESCRIPTION

FIG. 1 is a front elevational view of the pocketed security I.D. undergarment showing my new design;

In FIG. 2, the indicia indicated by broken lines are for illustrative purposes only and form no part of the claimed design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a front elevational view of the device with the separable front halves turned back to reveal the security pockets.
